Application May 4, 1945, Serial No. 591,860

15 Claims. (Cl. 11—1)

1

This invention relates to the manufacture of books and particularly to mechanism for securing the end leaves on a paper bound book.

In the manufacture of paper bound books, it has been customary to attach a fly leaf in place merely by the application of a narrow margin of glue on the book. The back and front end sheets of a book may also be made each of a double size sheet of paper previously folded on the center line, and one of the folded flaps may be pasted to the cover while the other remains free and thus forms the fly leaf. In the manufacture of such a book, it has been customary to apply the two double end leaves to the cover manually and then affix the cover on the book. In that procedure, the cover, previously cut to size, has been marked or scored for subsequent alignment of the end sheets; then adhesive has been applied to the paper cover; and following this, the operator carefully lays in place the end sheet which has been previously cut to size and folded in separate operations. When one end sheet has been attached to the cover, the latter is turned around and the second end sheet applied. Considerable skill, as well as a waste of time, is involved in assembling these parts manually.

In that old procedure, the signatures are gathered into a book and clamped together, and then the back is cut by a knife, thus leaving each of the sheets separate and unattached. While held in the clamps, glue is placed on the back edges of the assembled unconnected sheets of the book, and the book is inserted into the cover. For some books, a super or strip of crash is mounted on the back of the book before it is secured to the cover. A less durable book is made by attaching the cover directly to the glued edges of the book sheets without the aid of an intervening strip of crash. In the latter case, the book sheets are likely to become loose anywhere throughout the book, since there is nothing but the thin glued edge of each sheet to hold it in place. Also, if the crash is used, this has been located between the book and the end sheets, so that the edges of the crash often show in the completed book, and the construction is not as strong as it should be. The book tends to crack and to break near the back hinge. Further problems are presented in aligning the crash on the book back when this operation is done by hand. These various operations therefore involve an excessive amount of manual labor, which is expensive and seriously time wasting, and they do not provide a strong and durable book.

A primary object of this invention is to elimi-

2

nate various hand operations and to provide a method of making a paper covered book and particularly for securing the end leaves to the book cover, which will insure proper alignment and positioning of the end leaves and which will result in a strongly reinforced book of good appearance.

Another object is to provide a machine for applying both the end sheets and a reinforcing super or crash to a series of book covers in such a way that the operation may be carried on continuously, and which insures that the end leaves are assembled accurately and applied properly to each cover while the crash is inserted in such a location relative to the end leaves that a strongly reinforced product is thereby obtained.

Another object is to provide a machine which will perform automatically the various required operations expeditiously, accurately and continuously, so that a series of covers fed progressively thereto may each be provided with the end sheets and a reinforcing super and be fully prepared for mounting on a book.

Another object is to provide a new construction of paper covered book in which a crash or super is so secured to the cover and the end sheets that its edges are not visible in the finished product and the book structure is strong and durable and the cover will not be easily cracked or broken near the hinge. Further objects will be apparent in the following disclosure.

In accordance with our invention, we have made a paper bound book which has a super or strip of crash or other suitable reinforcing material secured to both the paper cover and the book in such a position that it not only reinforces the back of the book but also minimizes breakage of the cover near its hinge.

Referring to the drawings:

40 Fig. 1 is a perspective view of a new book structure, with parts shown exaggerated for clarity of illustration;

45 Fig. 2 is a similar view of the book cover, end leaves and crash in their attached relationship and prior to assembling the book therein;

50 Fig. 3 is a fragmentary view showing the method of assembling a series of covers with two continuous end leaves and a strip of crash and which are subsequently severed to provide the required book lengths;

Fig. 4 is a diagrammatic sketch illustrating a group of assembled book signatures;

Fig. 5 is a similar view after the folded ends have been severed therefrom;

Fig. 6 similarly shows such a book after glue

has been applied to the back edges of the book sheets;

Fig. 7 shows the relationship of the book of Fig. 6 mounted on the cover of Fig. 2;

Fig. 8 is a top plan view, with parts broken away, of a machine which will perform the various operational steps of assembling the cover, end sheets and reinforcing crash;

Fig. 9 is a vertical elevation of the same;

Fig. 10 is a somewhat diagrammatic fragmentary elevational view showing the operation of the device and the relationship of parts just prior to severing the end sheets;

Fig. 11 is a similar view showing the parts immediately after the severing operation has been completed; and

Fig. 12 is a similar view showing the relation of the parts when the flying carriage has reached the end of its travel prior to return to the initial starting position.

As shown particularly in Figs. 1, 2 and 7, our new type of paper bound book structure comprises a collection of book sheets, herein termed the book 1, mounted in a paper cover 2. Two V-shaped end sheets are inserted between the book and the cover. Each of these end sheets is formed of a folded sheet of paper made up of the parts 3 and 4. The part 3 forms the fly leaf and the part 4 is glued securely to the inner face of the cover. A strip of crash 5 made of a starch coated open mesh cloth or other suitable reinforcing super is held in place across the back of the book by means of the glue that attaches the end sheet portion 4 to the cover. As illustrated, the crash is much wider than the book 1, and a margin projects into the space between the cover 2 and the attached portion 4 of the end sheet. The book 1 is provided with a coating of glue 6 on the back edges of the assembled sheets, and the book is placed between the fly leaves (Fig. 7) and attached to the cover while the glue is still plastic. The glue 6 permeates the open mesh crash 5 and so attaches the crash both to the back of the book 1 and to the inner central back portion of the cover 2. Hence, the crash serves as a reinforcement for the back of the book as well as for the hinge portion of the cover, and it thereby minimizes the danger of the cover breaking at the point where it hinges. The construction of Figs. 1 and 7 is exaggerated in order to show the different parts clearly, but it will be appreciated that the end sheets, crash and cover with the associated glue lie in firm attachment without any spaces therebetween. In this construction, the crash 5 is concealed between the cover 2 and the attached end sheet portion 4 and it cannot be seen when the book is opened.

The book is made by assembling the signatures and then cutting the edges on the line *b*—*b* of Fig. 4 while the sheets are suitably held by clamps, thus leaving the sheets individually separate and unattached as shown in Fig. 5. The adhesive 6 applied to their lower edges (Fig. 6) serves to hold them together.

In accordance with our method of making such a book as illustrated in Fig. 3, two continuous strips of end sheet paper 7 may be folded in accordance with standard practice and then assembled with a continuous strip of crash 8 therebeneath and the previously cut covers 9 are pasted thereto. The folds of the end sheets 7 face inwardly and are spaced at the correct distance, so that the book may be put in place and be glued only to the crash. This procedure may be carried out continuously by feeding the covers

9 in a correct spacing into association with the end sheets after glue or other suitable adhesive has been applied either to the covers or to the under faces 4 of the travelling end sheets. After 5 the end sheets and crash have been attached to the covers, the end covers and crash are severed along the line *a*—*a* of Fig. 3. The cover with its attached parts has the general appearance shown in Fig. 2. After the book has been assembled in 10 the cover, the various parts may be further trimmed as desired.

This method of book manufacture may be carried out by means of various types of mechanism, but we have shown in Figs. 8 to 12 inclusive a 15 preferred form of machine which will accomplish these steps. Two continuous strips of end sheet paper 10 are drawn from suitable spools 11 rotatably mounted on vertical axles 12 on the framework of the machine. These two sheets of 20 paper pass over guide rolls 13 and then through two folding devices 14 of standard construction which serve to fold each continuous strip into a double strip having its two halves of equal width. Each folding device 14 comprises a strip of sheet metal which is arranged vertically and 25 parallel with the axis of the shaft 12 at its left hand end, and this metal sheet is bent medially and away from the center line of the machine so that at the right hand end it is V-shaped and has 30 two closely adjacent side portions 15 facing outwardly and horizontally. The paper is bent thereby into a V-shaped double strip. These double strips pass between a pair of suitably mounted pressure rollers 16 which crease the strip at its 35 central line. From there the lower flap 4 of the doubled strip 10 passes over the top surface of a glue roller 18 which applies glue or other suitable adhesive thereto in accordance with standard procedure. This roller 18 may be mounted on a suitable horizontal shaft supported on a tank 19 carrying the glue. The roller 18 dips directly into the glue and a wiper roll 20 spaced correctly from the roller 18 provides an even coating of the correct amount for transfer to the 40 paper. A presser roll 21 holds the paper against the glue roll. The two paper strips 10 pass in parallel arrangement around a guide roll 22 and through spacing guides 23 and then between two pairs of pressure rollers 24 and 25 which force 45 the glued sheets into contact with the book covers. As indicated particularly in Figs. 10 to 12, the non-glued end leaf 3 comes into contact with the lower roll and the glued leaf 4 is on the upper side. Here the glue coated leaf 4 50 meets a cover 30 arranged with its outer printed face up, so that the glued sheets will be applied to the under face thereof as the parts are fed forward between the driven pressure rolls 24 and 25.

55 The covers 30 are fed forward by a suitable automatic feed mechanism which may be of standard construction. This is illustrated in the drawings as comprising two spaced endless chains 31 having prongs 32 projecting upwardly therefrom which engage the rear edges of the covers and move them forward in a proper timed relationship. The prongs are so spaced as to feed the covers forward with a small space therebetween. The chains 31 are suitably carried on 60 supporting and driving sprockets 33 having a common axle mounted in the framework of the machine. The covers 30 are delivered to the feed rollers 24 and there meet the glued end sheets and crash coming up from beneath.

65 For making the preferred construction of book

shown in Fig. 1, a continuous strip of crash 36 or other suitable material is fed from a supply roll 37 suitably mounted for rotation on a horizontal axle 38 carried by the framework of the machine. This strip of crash is fed between the glued end sheets 4 and the under side of the cover 30. It is not necessary that glue be applied to the crash, since the glue applied to the end sheet portion 4 will hold the crash in place. Also, the glue later applied to the back of the book will pass through the crash and secure it not only to the book but to the inner face of the cover 30. These three elements, the book cover, the crash and the folded end sheets pass beneath the pressure rolls 24 and 25 and are thus forced into a firm contact. The folded end sheets 10 are held in a properly spaced relationship by having the folders 14 properly spaced and by having the U-shaped guide 23 adjustably positioned adjacent to the roll 24.

The next step in the mechanical procedure involves severing the folded end leaf strips and the crash as they travel along continuously and uniformly. Although we may employ a rotary knife which is so shaped and timed in its operation as to sever the sheets between the covers, we have illustrated in the drawings what we term a flying shear that is arranged to travel at the speed of the moving paper at the time of the severing operation. This construction comprises a knife 40 mounted for vertical reciprocation on the flying carriage 41 which is carried by means of two pairs of rollers 42 riding on parallel tracks 43 carried by the framework of the machine. The knife 40 is removably secured to an L shaped cross member 44 which is fastened at its opposite ends to two vertical slides 45 riding in parallel slideways 46 in the framework. The lower ends of these slide members 45 are each connected by a link 47 with a rocking arm 48 that is arranged to actuate the cutter knife 40 at the proper moment.

A presser foot 50 (omitted in Fig. 8) is mounted on the lower end of a sliding pin 51 which passes through the horizontal portion of the L shaped cross bar 44, and it is held in place by nuts 52 thereon. A spring 53 holds the presser foot in its lowermost position as permitted by the nuts 52. This presser foot is intended to be brought down into engagement with the top surface of the book cover 30 just prior to the moment when the knife travels downwardly to sever the end sheets and crash, and the presser foot remains in contact with the paper until after the severing operation has been completed and the knife has been withdrawn, as is shown in Figs. 10 and 11.

The lower stationary knife edge 54 is so located beneath the travelling paper that the upper knife 40 will shear against it to cut the paper as it travels past. The top surface of the plate 55, which has the knife edge 54, serves as a table support for the paper and against which the presser foot 50 holds the paper during the cutting operation. A tension spring 56 (Fig. 10) connects between the slide 45 and the carriage 41 and aids in holding the knife and the presser foot in an uppermost position except during the cutting operation.

The covers, which have been previously printed and otherwise prepared, may be initially cut to such a size that they should not be further cut during this severing operation. Hence, we so arrange and time the parts of the operating mechanisms that the covers are fed forward with a slight spacing, such as $\frac{1}{16}$ ", which permits the

knife 40 to cut only the end sheets and crash between the spaced edges of the covers. This timing of the various operating parts is accomplished by driving all of the mechanisms from a single motor 60 suitably supported on the framework of the machine (see Figs. 8 and 9). The motor is connected by a drive chain 61 to a sprocket 62 on a crankshaft 63 which has a further gear thereon connected by a chain 64 to a sprocket 65 on a counter-shaft 66. From a sprocket on the counter-shaft 66 a further chain 68 runs to a sprocket 69 on another shaft which has a gear 70 thereon meshing with a further gear 71 mounted on a parallel shaft and which thus reverses the motion and transmits driving power through a chain 72 to the sprocket 73 on the shaft 74 that carries the glue rollers 18. Another chain 75 driven from the counter-shaft 66 drives the upper one of the pinch rolls 16 which serve to crease the folded paper as it comes from the V-shaped folder 15.

The shaft 63 which is driven directly from the motor has two crank arms 77 connected by pins with pitmans 78 which are pivotally connected at their right hand ends to opposite sides of the carriage. Thus, as the shaft 63 revolves, the crank arms 77 cause the flying carriage 41 to move back and forth once for each revolution of the crankshaft. The length of the crank arm 77 is such that it moves the carriage forward through a distance equal to the length of the cover 30 that is being fed forward by the pressure rolls 24 and 25, and the cranks 77 are so located on their shaft 63 that the carriage is moved at maximum speed and substantially that of the travelling paper at the moment when the knife severs the paper.

The vertical oscillation of the knife 40 is effected by means of two revolving arms 80 mounted on short shafts 81 carried in suitable bearings 82 on the framework at the sides of the flying carriage. Each shaft 81 carrying the striker arm 80 is revolved by a drive chain 83 (Figs. 8 and 9) driven from the main counter-shaft 66. The two rocking arms 48 (Figs. 9 to 12) which move the knife slide up and down are secured to a rock shaft 84 which has two pairs of striker arms 85 and 86 (not shown in Fig. 8) fixed thereto and each having a suitably mounted roller on its end. This rock shaft 84 is rotatably mounted in bearings on the flying carriage. The parts are so located and timed that, as shown in Fig. 10, the striker arms 80 revolve downwardly into contact with the rollers on the arms 85 and cause the knife to cut the three strips only between the two adjacent covers 30 that are fixed relative to and are travelling with the flying carriage as it is moved forward by the crank arm 78. The striker arm 80 gives a quick blow to the arm 85 and thrusts the knife downwardly to sever the paper and this happens while the arm 85 is travelling toward the left with its supporting carriage. The steps of the severing operation are shown in Figs. 10 to 12. As indicated in Fig. 11, the roller on the arm 86 (moving with the carriage) is approaching a cam surface 88 on a stationary part of the framework as the cutting is completed. The roller on the arm 86 strikes this cam because of the forward motion of the carriage and thus kicks the operating arm 85 again to the left. At the same time, it raises the rocking arm 48 and thus thrusts the cutter knife upwardly and releases the presser foot from contact with the paper. This motion is completed (Fig. 12) by the time the crank arm 78 passes over dead center

around the drive shaft 63 and the carriage is returned to the right for another cutting operation. The timing of the feed mechanism which provides the covers is accomplished through the counter-shaft 66 which drives a longitudinal shaft 90 (Fig. 8) through a pair of bevel gears 91. The shaft 90 is connected through an adjustable coupling 92-93 and a second pair of bevel gears 94 with a cross shaft 95 that carries and drives the two chain sprockets 33. One of the parts 92 has an arcuate slot and the other a bolt which are so arranged that the parts 92 and 93 may be rotated through a slight distance relative to each other and then be clamped together by the bolt. This serves to adjust the timing of the cross shaft 95 and the drive sprockets 33 with the operation of the knife that is likewise driven from the counter-shaft 66.

At the left hand end of the machine is a set of endless belts 96 suitably carried on pulleys on a cross shaft 97 driven by means of a belt 98 from the main counter-shaft 66. The upper run of each belt 96 passes over an idler on the shaft 99 which slopes the belts upwardly from the right hand idler pulleys 100 which are located somewhat below the horizontal run of the paper and covers at the right hand of the cutter knife. This permits the covers 30 to drop down somewhat onto that sloping run of the belt at the time of the severing operation. A set of idler rolls 102 engage the top surface of the cover parts and holds them against the driven belts 96, so that they are removed from the operating zone. A chain and sprocket drive 104 connects the shaft 95 with the first set of press rolls 24, and a further chain 106 connects the axle of the top roll 24 with the axle of the upper roll 25. These rolls are of such sizes and speed that they move the paper strips and covers forward by the length of one cover plus $\frac{1}{8}$ of an inch per slicing movement of the knife.

The operation of the machine has been fully set forth above. Although the crash reinforcement is to be used in our preferred book construction, it of course is evident that this crash may be omitted and the machine may be operated for assembling the covers and end leaves for making a cheaper type of book. It may also be noted that the quantity of glue regulated by the adjustable wiper roll 20 may be made sufficient to pass through the open mesh of the crash strip and engage the inner face of the cover and thereby secure the lower portion 4 of the end leaf not only to the crash but also to the cover so as to secure the three parts together. Also, an excess of glue on the back of the book will tend to seep laterally and make sure that the crash is fully secured in place. The machine may also be used for assembling the parts of a board cover, wherein the cover consists of paper board with or without a cloth or other covering.

If desired, a further strip of paper, or other suitable impervious material, may be fed forward from a supply roll and inserted between the crash super and the cover at the time of assembly. The width of the supplemental paper strip preferably equals, or is less than, the width of the space between the folded edges of the end sheets. This prevents the glue on the back of the book from penetrating to the inner surface of the cover and so leaves the cover backbone free from the book. In that case, the book is glued only to the super, and the super is secured to the cover by the end sheets glued thereover.

It will therefore be appreciated that various

modifications may be made in the method as well as the machine above described without departing from the scope of this invention and that the above description of the method and a preferred embodiment thereof and of the covered book made thereby is not to be interpreted as imposing limitations on the appended claims.

We claim:

1. The method of making a book cover comprising the steps of progressively moving forward two strips of paper which are folded medially to form end sheets and guiding them so that their folded edges are adjacent to each other but spaced by approximately the thickness of a book to be covered, guiding a reinforcing super strip into position between the spaced strips and progressively gluing one flap of each folded strip to a series of covers fed forward in sequence with the edges of the super secured in position beneath the folded edges of the end sheets.

2. The method of making a book cover comprising the steps of progressively moving forward two strips of paper which are folded medially to form end sheets and guiding them so that their folded edges are adjacent to each other but spaced by approximately the thickness of a book to be covered, applying adhesive progressively to one flap of each folded strip, progressively moving the two strips into adhering contact with a series of paper covers, simultaneously feeding a reinforcing super strip into contact with each cover and with its edge portions beneath the inner folded edges of the two end sheet strips so that the adhesive on the latter holds the super in place, and thereafter severing the strips and providing a series of covers having two spaced fly leaves attached thereto by the adhering flaps and a reinforcing super extending between the fly leaves and secured beneath the adhering flaps.

3. The method of making a book comprising the steps of progressively feeding forward two strips of paper which are folded medially to form end sheets and guiding them so that their folded edges are adjacent to each other but spaced by approximately the thickness of a book to be covered, applying adhesive progressively to one flap of each folded strip, feeding a set of covers serially in spaced arrangement, progressively moving the two strips into adhering contact with the covers, simultaneously feeding a reinforcing super strip into contact with each cover and with its edge portions beneath the inner folded edges of the two end sheet strips so that the adhesive on the latter holds the super in place, thereafter severing the strips between the covers and providing a series of covers having two spaced fly leaves attached thereto by the adhering flaps and a reinforcing super extending between the fly leaves and secured beneath the adhering flaps, and thereafter applying adhesive to the back edge portions of assembled book sheets and pressing the same into contact with the super on the cover while located between the fly leaves.

4. A machine for assembling parts of a series of book covers comprising mechanism for continuously feeding forward two extensive paper strips which are folded medially to form end sheets, means for guiding the folded strips with their folded edges juxtaposed in parallelism and spaced by approximately the thickness of each book to be covered, feed mechanism for feeding a set of separate covers serially forward into contact with the moving folded strips, means for applying adhesive which will secure the end sheets to the covers, means for pressing one flap of each

folded strip onto each cover, and means for simultaneously feeding a continuous super strip in position between the moving end sheets and the covers and attaching it thereto where it will reinforce the back of each of the books.

5. A machine for assembling parts of a book cover comprising mechanism for progressively folding two paper strips medially to form end sheets, means for progressively moving the strips forward with their folded edges adjacent to but spaced from each other, means for applying adhesive to the face of one flap of each folded strip, means for forcing the adhesive coated faces into contact with a series of covers progressively fed thereto and thereby providing fly leaves secured to the cover by the adhering flaps, and means for feeding a super strip into position adjacent to the cover between the fly leaves and beneath the folded edge portions of the strips so that each super is secured in position by the adhesive on the under face of the end strip.

6. A machine for assembling parts of a book cover comprising mechanism for progressively moving forward two paper strips folded medially to form end sheets, means for guiding the strips so that their folded edges are adjacent to but spaced from each other, means for applying adhesive to one face of each folded strip, means for moving the adhesive coated faces into contact with a series of covers progressively fed thereto and thereby providing fly leaves secured to the cover, means for feeding a super strip into position adjacent to the cover between the fly leaves and beneath the folded edge portions of the strips so that the super is secured in position by the adhesive on the under face of the end sheet, and cutter mechanism for progressively severing the super and end sheet strips and thereby providing a series of covers with the end sheets and super secured thereto.

7. A machine for assembling parts of a book cover comprising mechanism for progressively feeding two folded paper strips into contact with a series of covers serially presented thereto, means for progressively inserting the edges of a reinforcing super strip beneath the folded edges of the end sheets and into contact with the middle portion of the book cover, means for applying adhesive so as to secure the end sheets and super to the cover, and cutter mechanism which operates intermittently as the covers and strips move forward continuously for severing the strips and providing a series of covers having the end sheets and supers attached thereto.

8. A machine for assembling parts of a book cover comprising mechanism for progressively feeding two folded paper strips into contact with a series of covers serially presented thereto, means for progressively inserting the edges of a reinforcing super strip beneath the folded edges of the end sheets and into contact with the middle portion of the book cover, means for applying adhesive so as to secure the end sheets and super to the cover, cutter mechanism which intermittently operates as the covers and strips move forward for severing the strips and providing a series of covers having the end sheets and super attached thereto, and power driven mechanisms operating in timed relationship which cause the covers to be fed to the strips in a spaced relationship and the severing knife to cut the strips only between the spaced covers.

9. A machine for assembling parts of a book cover comprising mechanism for progressively feeding forward two folded paper strips arranged

with their folded edges adjacent to but spaced from each other, means for applying adhesive to one leaf of each folded strip, means for feeding a strip of reinforcing super progressively into contact with a set of covers serially presented thereto in spaced relationship, means for attaching the adhesive coated leaves of the folded strips to the covers and the outer edges of the super and thereby providing fly leaves attached to the cover by said adhering leaves, and timed mechanism for severing the strips only between the spaced edges of adjacent covers as the parts are fed forward.

10. A machine for assembling parts of a book cover comprising power driven mechanism for progressively feeding a set of separate covers serially in spaced arrangement, means for moving two extensive folded strips of end sheets forward continuously with their folded edges in parallelism and spaced by approximately the thickness of the book to be covered, means for adhesively attaching the end sheets to the separate covers as the parts move forward at a uniform rate, and power driven cutter mechanism which operates intermittently in timed relation with the cover feed mechanism to cut said strips between the spaced covers without interrupting the forward movement of the covers and strips.

11. A machine for assembling parts of a book cover comprising mechanism for moving forward two folded paper strips with their folded edges adjacent to but spaced from each other, means for applying adhesive to an under leaf of each folded strip, means for feeding covers serially in spaced relationship, means for presenting the adhesive bearing faces of the leaves against the inner sides of the cover, means acting simultaneously to insert a strip of reinforcing super into contact with the cover and with its edges beneath the folded edge portions of the strips so that the super is attached to the cover by means of the adhesive on the folded leaves and its edge portions are concealed, and timed mechanism for intermittently severing the strips between the spaced edges of the covers as the parts move continuously forward.

12. The method of making a book cover comprising the steps of continuously folding two separate extensive strips of paper to form two sets of double end sheets for a series of book covers, guiding the folded sheets into a spaced relationship with their folded edges juxtaposed in parallelism and spaced by approximately the thickness of a book to be covered, feeding a series of separate covers forward in sequence into position with the inner surface of each cover in contact with one leaf of each folded end sheet and gluing each cover to the adjacent leaf of each folded end sheet.

13. The method of making a book cover comprising the steps of folding two strips of paper medially to form double end sheets, continuously feeding them forward and guiding them into a spaced relationship with their folded edges juxtaposed in parallelism and spaced by approximately the thickness of the book to be covered, progressively feeding a cover and a super strip to positions where the inner face of the cover contacts with one leaf of each folded end sheet and the super strip is located between the cover and the folded end sheets and its edges are overlapped by the sheets, and gluing one flap of each folded end sheet to the cover and to the underlying edge of the super strip.

14. The method of making a book cover comprising the steps of continuously moving forward

11

two extensive strips of paper folded medially to form end sheets, guiding them continuously into a spaced relationship with their folded edges juxtaposed in parallelism and spaced by approximately the thickness of the book to be covered, progressively feeding a series of separate covers forward with the inner face of each cover located adjacent to one page of each folded end sheet strip, adhesively securing the strips of end sheets to the covers, and thereafter severing the end sheet strips between the covers.

15. The method of making a book cover comprising the steps of continuously moving forward two extensive paper strips which are folded medially to form a series of end sheets, guiding them into a spaced relationship with their folded edges juxtaposed in parallelism and spaced by approximately the thickness of the book to be covered, progressively feeding forward a series of separate covers and a continuous reinforcing super strip to positions where the two edges of the super strip are located between the moving strips of end sheets and each cover and the inner face

12

of each cover contacts with one page of each folded strip, adhesively securing the series of covers and the continuous super strip to the moving end strips as thus located, and thereafter severing the strips between the covers.
